UNITED STATES PATENT OFFICE

112,063

DESIGN FOR A MONUMENT

Robert A. Grieve, Denver, Colo.

Application August 6, 1938, Serial No. 79,161

Term of patent 14 years

To all whom it may concern:

Be it known that I, Robert A. Grieve, a citizen of the United States, residing in the city and county of Denver and State of Colorado, have invented a new, original, and ornamental Design for a Monument, of which the following is a specification, reference being had to the accompanying drawing, forming part thereof,

I claim:

The ornamental design for a monument, as shown.

ROBERT A. GRIEVE.
